CASEMENT WINDOW OPERATOR

Gotthard Hagstrom, Westville, Conn., assignor to
The H. B. Ives Company, New Haven, Conn., a
corporation of Connecticut

Application September 19, 1938, Serial No. 230,546

4 Claims. (Cl. 268—119)

This invention relates to a casement window operator, and more particularly to that type of operator whereby the window sash is operable by a crank or the like, so that a screen may be provided on the inside of the window sash without interfering with the opening of the sash by the operator, which may still be effected by a crank, the spindle of which passes through the screen.

Devices of this character have heretofore been provided, but have had certain disadvantages in their construction and operation. Those devices which have operated satisfactorily have been relatively expensive to manufacture, and the high price for which they were sold has militated against a wide market.

Moreover, in some instances the prior devices have been difficult to assemble and to place in operating position upon a window, and in some instances it has been difficult to draw the sash to a tightly closed position.

One object of the present invention is the provision of an efficient casement window operator which may be manufactured at a relatively low cost.

Another object of the invention is the provision of a casement window operator which may be economically manufactured and which at the same time will be efficient in operation, and be capable of being easily and readily installed in place.

Another object of the invention is the provision of a casement window operator provided with an operating arm actuated by a worm gear mounted in a casing on the window frame, the casing also being provided with a worm operatively engaged with the gear, and the casing, worm, gear and arm being of such construction that the parts may be economically manufactured and readily assembled, so that the operator may be marketed at a relatively low price.

To these and other ends the invention consists in the novel features and combinations of parts to be hereinafter described and claimed.

In the drawing:

Fig. 1 is a front elevational view of a window provided with my improved operator;

Fig. 2 is a sectional view through the window showing a top plan view of the window operator;

Fig. 3 is a sectional view on line 3—3 of Fig. 2;

Fig. 4 is a sectional view on line 4—4 of Fig. 3;

Fig. 5 is a view similar to Fig. 3 but showing the worm and gear casing, with the operating parts removed;

Fig. 6 is a top plan view of the worm gear;

Fig. 7 is a sectional view of the gear on line 7—7 of Fig. 6;

Fig. 8 is a fragmentary top plan view of the operating arm connected to the gear; and

Fig. 9 is a sectional view of one end of this arm on line 9—9 of Fig. 8.

To illustrate a preferred embodiment of my invention, I have shown a window frame 10 to which is hinged at 11 a sash 12, these being the usual parts of an ordinary casement window. To the sash 12 is secured a tubular guide member 13 by means of screws 14, and within this tubular guide member is a slider 15 carried by a swinging arm 16. The above parts, with the exception of the arm 16, may be of the usual construction, for example, of the construction shown in the Hendrick Patent No. 2,128,483, granted August 30, 1938, so that no further description thereof is necessary herein.

On the window casing is mounted a housing 17, this housing being provided with a base portion 18 and a chamber 19 within which a worm 20 is mounted. The upper side of the housing projects forwardly from the chamber 19, as shown at 21 in Figs. 3 and 5, to lie parallel to and spaced from the base plate 18, so that the worm wheel may be positioned between these two parts, as will be hereinafter described.

The housing is provided with front and back walls 22 and 23 at the front and back of the chamber 19, and it will be seen from reference to Figs. 3 and 5 that there is an opening 24 in the base 18 of the housing leading into the chamber. The walls 22 and 23 are recessed on their interior faces to receive the end necks of the worm, as shown, for example, in Fig. 5 in connection with the wall 22. As shown, each of these recesses comprises an upper portion 25 of substantially semi-circular shape, the rear wall of this portion of the recess terminating in a shoulder 26 beyond which the wall is inclined outwardly, as shown at 27, to enlarge the lower portion or mouth of the recess. The walls 22 and 23 are provided with openings 28 and 29 which register with the opening 30 in the worm 20. It will be understood that the upper semi-circular portions 25 of the recesses in the walls are of a size to snugly receive the necks 31 and 32 of the worm 20.

The chamber 19 is also provided with an opening 33 at its forward portion which communicates with the space between the upper plate 21 and the base plate 18, and between these two plates a gear 35 is rotatably mounted by means of the screw 36. It will be noted from Fig. 3 that this gear projects rearwardly through the open-

ing 33 into the chamber 19, so that the gear teeth may be properly engaged by those of the worm. It will also be noted that the gear teeth 37 are of special form, as shown in Fig. 7, in that they 5 are milled into the side of the gear and are of segmental shape, and are not cut through the upper and lower faces of the gear.

As shown in Fig. 7, the gear is provided with a central opening 38 to receive the pin 36, and is 10 provided with an annular recess 39 milled therein from its upper face, this recess surrounding the opening 38, and leaving a hollow sleeve or post 40 about this opening, the upper end of which post is slightly cut away so that it does not extend to the upper surface of the gear. As shown in Fig. 6, slots 41 and 42 are also cut through the upper face of the gear to communicate with the annular recess 39, which slots open through the peripheral edge of the gear and which provide 15 therebetween an upstanding integral gear portion or post 43 the top of which is also cut away. It will be apparent that the slots 41 and 42 together with the rear portion of the recess 39 form in effect a U-shaped recess opening upwardly 20 through the face of the gear and also through its periphery.

The arm 16, as shown more particularly in Figs. 3, 8 and 9, is provided with side flanges 45, so that this arm is of channel-shaped form in 30 cross-section and may readily be formed by a stamping operation. At its rear end the arm is provided with an upwardly offset portion 46 having an opening 47 and a substantially semi-circular end portion 48. It will be observed that the 35 flanges 45 are continued around the end portion of the arm to be joined in a substantially U-shaped depending member at this end of the arm.

The above construction provides a simple, convenient and efficient way to secure the arm 16 rigidly to the gear so that the turning of the gear 40 will effect rotation of the arm. The arm is placed with its opening 47 in registration with the opening 38, and the flange 45 at the rear end of the arm pressed downwardly into the annular 45 recess 39. It will be noted that the slots 41 and 42 permit the entry of the side flanges into this recess, and permit this method of assembling the arm and gear, as shown in Fig. 3. It will also be observed that the portion 43 of the gear fits snug- 50 ly between the flanges 45 on opposite sides of the arm 16, so that these flanges will be supported internally, and movement of the gear will bring pressure upon both sides of the flanges, and upon both flanges evenly, regardless of the direction 55 in which the gear is turned. There will thus be no tendency to deflect or distort the flanges from their normal positions.

In the assembly of the worm into the chamber 19 of the housing, the worm is inserted through 60 the lower opening 24, the necks 31 and 32 being first engaged by the walls 27 of the recesses in the front and rear walls of the housing. As the worm is pushed upwardly, as will be seen from Fig. 5, it is also moved slightly forwardly, and at 65 the time that the necks reach the shoulder 26, parts of the worm teeth will have moved upwardly to a point opposite the opening 33 so that the worm will have room to move forwardly, and can thereafter be pressed vertically upwardly until its necks are snugly received in the recesses 25, with the worm opening 30 opposite the openings 28 and 29 in the end walls. The shaping of the 70 recesses in the end walls of the chamber 19 in this way provides for the strengthening of the 75 housing, as the base plate 18 may be carried rear-

wardly at the point 18a to a further extent at one side of the opening 24, thus giving a greater amount of metal in the casing at this place, and providing a much stronger construction.

After the worm has been positioned as described above, and the arm 16 and gear 35 have been assembled, also as above described, the gear is inserted between the base plate 18 and the upper plate 21, and moved rearwardly until its teeth are engaged by the teeth of the worm 18, 10 and the pin or screw 36 put into place. Due to the shape of the gear teeth 37, it will be apparent that the worm will be held in place by the engagement of its teeth with those of the gear, and no other provision is necessary, therefore, for 15 preventing the worm moving downwardly out of its position in the slots in which its end necks are engaged.

The worm may be rotated by means of a crank 50 having a non-circular spindle 51 which may 20 be inserted in the similarly shaped opening 30 of the worm, and it will be apparent that when the worm is rotated the gear 35 will also be rotated, and due to the rigid connection of the arm 16 therewith, the latter will be caused to swing about 25 the pin 36 and thus operate the window sash. It will also be noted that all the parts of the operator are of simple construction and are so designed that they are susceptible of economical manufacture, the result being a very efficient 30 structure which can be relatively cheaply made.

While I have shown and described a preferred embodiment of my invention, it will be understood that it is not to be limited to all of the details shown, but is capable of modification and 35 variation within the spirit of the invention and within the scope of the appended claims.

What I claim is:

1. In a casement window operator, a housing, 40 a gear rotatably mounted in the housing, actuating means for said gear, a channel-shaped arm having depending flanges at its side edges, and said gear having upwardly opening recesses in which said flanges lie to rigidly connect said arm and gear.

2. In a casement window operator, a housing, 45 a gear rotatably mounted in the housing, actuating means for said gear, an arm having a depending U-shaped flange adjacent one end, and said gear having a U-shaped recess opening 50 through its upper surface and its peripheral face to receive said flange and rigidly connect the gear and arm.

3. In a casement window operator, a housing, 55 a gear rotatably mounted in the housing, actuating means for said gear, a channel-shaped arm having depending flanges at its side edges which extend about the rear end of the arm, and said gear being cut away at its upper surface to receive said arm, and having an upwardly opening 60 recess therein to receive said flanges to rigidly connect said gear and arm.

4. In a casement window operator, a housing, 65 a gear rotatably mounted in the housing, actuating means for said gear, a channel-shaped arm having depending flanges at its side edges which extend about the rear end of the arm, said gear being cut away at its upper surface to receive said arm, and having an upwardly opening recess 70 therein to receive said flanges to rigidly connect said gear and arm, and a portion of said gear lying between said side flanges of the arm to give internal support thereto.
